(54) **TURPENTINE, EXTRACTING BY STEAM**

(76) Inventor: **Isaiah Jennings**

Isaac Herring

The subscriber names to the above Letters Patent
and making part of the same containing a descrip-
tion in the words of the said Isaac Herring him-
self of his improvement in the process for the extract-
ing of spirits of turpentine and also of separating the
resin from fine wood.

To all to whom it may concern.

I wish to inform that Mr. Isaac Herring of the
the City of New York in the City of New York
have invented a new and improved process for extract-
ing spirits of turpentine and also for separating the resin
from fine wood, and I do hereby declare that the
following is a full and exact description thereof.
Take this resin wood in logs or pieces and reduce
the same to powder or fine sand dust by means of
rotating mills or in any other way in which this
reduction can be effected and when I wish to separate
the spirit of turpentine alone therefore I submit it
to the requisite degree of heat in a still of any construc-
tion adapted to the distillation of such spirits, put-
ting into the still along with said powder such quan-
tity of water as may be requisite in the operation. The
residuum consisting of the lignous portion and
the resin will, I have said, be well adapted to the
purpose of making gas for the production of artificial light.
When I wish to obtain the resin as well as the spirit of
turpentine, I put the wood, reduced to powder into mills
or other comminuting vessels, and pass on it a sufficient
quantity of spirits of turpentine to separate by distilling
the crude turpentine therefore, keeping such heat as the
vessel can bear to prevent evaporation, when the spirit
thus passed is drawn off and distilled in the usual

may a perfectly pure acetin still constitute the residue
in the still, the stillings in the walls are afterwards to be
put into a still and the spirits driven off. What
I claim as my invention in the article described pro-
cess is the extracting of the spirit of turpentine in the spirit
of turpentine and acetin from pine wood after reducing
the wood into fine powder, strands or shavings in this
manner or upon the principle herein set forth.

Witnessed
